(57) **CLAIM**

The ornamental design for a paint tray, as shown and described.

DESCRIPTION

1. Paint tray
2. Liner for paint tray
3. Paint tray
4. Liner for paint tray
- 1.1 : Perspective
- 1.2 : Right
- 1.3 : Top
- 1.4 : Bottom
- 1.5 : Front
- 1.6 : Bottom Perspective;
- 2.1 : Perspective;
- 2.2 : Front
- 2.3 : Top
- 2.4 : Left
- 2.5 : Bottom
- 3.1 : Perspective;
- 3.2 : Front
- 3.3 : Right
- 3.4 : Top
- 3.5 : Bottom
- 3.6 : Bottom Perspective;
- 4.1 : Perspective;
- 4.2 : Front
- 4.3 : Top
- 4.4 : Left
- 4.5 : Bottom

Designs 1 and 3: paint trays with elevated, sloped rolling surface for optimal distribution of paint onto roller; distinctive second compartment for paint tools also provides more

(Continued)

stability; designs 2 and 4: disposable liners for sturdy trays that neatly follow the shape of these trays.

1 Claim, 22 Drawing Sheets
